Harriet L. Brann
INVENTOR

BY Victor J. Evans

WITNESS:

ATTORNEY

UNITED STATES PATENT OFFICE.

HARRIET L. BRANN, OF DES MOINES, IOWA.

HAIR CURLER.

Application filed August 15, 1923. Serial No. 657,584.

To all whom it may concern:

Be it known that I, HARRIET L. BRANN, a citizen of the United States, residing at Des Moines, in the county of Polk and State of Iowa, have invented new and useful Improvements in Hair Curlers, of which the following is a specification.

This invention relates to a device for curling hair, the general object of the invention being to provide means for clamping a lock of hair so that the lock can be wrapped around the device and means for holding the device in place with the lock wrapped around the same.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figures 1 and 2 are views showing how the device is used.

Figure 3 is a view of one form of the invention with the parts in partly open position.

Figure 4 is a view of another form of the invention with the parts in closed position.

Figure 5 is a view of another form of the invention.

Figure 6 is a view of a further form.

Figure 7 is a view of another form.

Figures 8 and 9 are views of a further form.

Figures 10, 11 and 12 are views of a form of the invention made of wire.

As shown in these views the device consists of a pair of jaw members 1 and 2 which are arranged to clamp a lock of hair between them so that the lock can be wrapped around the device and a hinged member 3 which is arranged to be held to one of the jaw members by a hook 4 so that the device can be held with the lock of hair wrapped around the same. Figures 1 and 2 show how the device is used and the hair can be rolled upon the device in either direction according to the desired position of the curl. In the form shown in Figure 3 the jaws 1 and 2 are formed from a flat piece of metal

doubled upon itself with the hook 4 formed upon the extended end of the jaw 1. The jaws are adapted to be held in closed position by a clip 5 which is slidably mounted on the jaw 1 and is adapted to engage the reduced end of the jaw 2. The member 3 is formed of a round bar which has one end passing through a hole in the looped end of the strip forming the jaws 1 and 2 and bent over to form a hinge. The other end of this member will engage the hook 4.

The device shown in Figure 4 is somewhat similar to that shown in Figure 3 excepting the hook 4 is located at one side of the jaw 1 instead of the center of the end thereof.

The device shown in Figure 5 is similar to that shown in Figure 4 with the exception that the looped end 6 of the member 3 is passed through the eye formed by the looped end of the strip forming the jaws 1 and 2 instead of passing this part through a hole in the strip. In this form of the invention the member 3 is of waved construction as shown at 6'.

In the form shown in Figure 7 the hook 4' is formed on the clip 5'. In other respects this form of the invention is similar to those before described.

In the modification shown in Figure 6 an S-shaped hook 5'' is formed on the end of the lower jaw so that the third member can be held in engagement with either the jaw 1 or the jaw 2, this member being so connected that it can be swung entirely around on its hinge.

In the form of the invention shown in Figures 8 and 9 the jaws 1' and 2' are of channel shape in cross section so that the curl will be given a waved effect. In this form also the two jaws are movably held together by the looped end of the member 3' which passes through holes in said jaw members.

In the modification shown in Figures 10, 11 and 12 the device is formed of wire, as shown at 7, the two jaw members being held together by a clip 8 which is slidably mounted on the lower jaw and the third member being formed with a single strand of wire which is hingedly connected with the jaw members by having its looped ends threaded through coils formed in said members. It engages a hook 9 formed at the front end of the main jaw member. In most of the forms the two jaw members are so connected to-

gether that they will spring open as soon as the upper jaw is released from the clip.

This device will act to curl and wave bobbed hair as well as long hair and it is especially useful on short strands of hair. The third member acts to hold the device in place with the hair wrapped around it so that there is no danger of the device being released from the hair.

10 It is thought from the foregoing description that the advantages and novel features of my invention will be readily apparent.

I desire it to be understood that I may make changes in the construction and in the 15 combination and arrangement of the several parts, provided that such changes fall within the scope of the appended claims.

What I claim is:—

1. A device of the class described comprising 20 a pair of jaw members, a clip for holding the jaw members together, a hook on one of the jaw members, a member hingedly con-

nected with the jaw members and adapted to have its free end placed under the hook.

2. A device of the class described comprising 25 a pair of jaw members, a clip slidably mounted on one jaw member and adapted to engage the end of the other member for holding the jaw members together, a hook carried by the lower member at its outer end, a bar hingedly connected with the jaw members 30 at their connected ends and having its free end adapted to be placed under the hook.

3. A device of the class described comprising 35 a pair of jaw members for clamping a lock of hair between them, a third member hingedly connected with the jaw members so that it can be swung against the outer face of either member and a double hook on the outer end of one jaw member for receiving 40 the outer end of the third member.

In testimony whereof I affix my signature.

HARRIET L. BRANN.
